(57) **CLAIM**

The ornamental design for a multi-media container as shown and described.

DESCRIPTION

1. Multi-media container

Fig. 1.1 is a front, right, and top perspective view of a multi-media container showing my new design;

Fig. 1.2 is a front elevational view thereof;

Fig. 1.3 is a rear elevational view thereof;

Fig. 1.4 is a left side view thereof;

Fig. 1.5 is a right side view thereof;

Fig. 1.6 is a top view thereof;

Fig. 1.7 is a bottom view thereof; and,

Fig. 1.8 is a rear, left, and bottom perspective view thereof.

The broken (dashed) lines show portions of the multi-media container that form no part of the claimed design.
